Primary Examiner — Elizabeth J Oswecki*Assistant Examiner* — Yelizaveta Y Masalimova(74) *Attorney, Agent, or Firm* — Suzanne Kikel, Patent Agent(57) **CLAIM**

The ornamental design for a sandal, as shown and described.

DESCRIPTION

FIG. 1 is a front perspective view of a first embodiment of a sandal showing my new design;

FIG. 2 is an exploded front perspective view of a second embodiment thereof;

FIG. 3 is a top plan view of the sandal of FIG. 1;

FIG. 4 is a top plan view of the sandal of FIG. 2;

FIG. 5 is a front elevational view of the sandal of FIG. 1; and,

FIG. 6 is an exploded, front elevational view of the sandal of FIG. 2.

The broken lines showing in the figures of the flowers and sandal depicts environmental subject matter and forms no part of the claimed design.
